(57) **CLAIM**

The ornamental design for a activity scarf, as shown and described.

DESCRIPTION

FIG. 1 is a front top left perspective view of a activity scarf; FIG. 2 is a rear bottom right perspective view thereof, showing the side of the scarf that contacts the face of the wearer;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is a front left perspective view of the scarf of FIG. 9, illustrating the activity scarf in a secured configuration for wearing.

The broken lines shown in the drawings depict portions of the activity scarf that form no part of the claimed design. The broken lines in FIG. 9 showing a head and shoulders depict environment and form no part of the claimed design.
